US00D831831S

(12) **United States Design Patent** (10) Patent No.: **US D831,831 S**
Newhouse et al. (45) Date of Patent: **** Oct. 23, 2018**

(54) **BASE FOR MEDICAL DEVICE
ELECTRONIC MODULE**

(71) Applicant: **DexCom, Inc.**, San Diego, CA (US)

(72) Inventors: **Todd Andrew Newhouse**, San Diego, CA (US); **Ryan Schoonmaker**, Oceanside, CA (US)

(73) Assignee: **DexCom, Inc.**, San Diego, CA (US)

(**) Term: **15 Years**

(21) Appl. No.: **29/611,665**

(22) Filed: **Jul. 24, 2017**

Related U.S. Application Data

(63) Continuation of application No. 29/532,767, filed on Jul. 9, 2015, now Pat. No. Des. 794,801.

(57) **CLAIM**

The ornamental design for a base for medical device electronic module, as shown and described.

DESCRIPTION

FIG. 1 is a top perspective view of an embodiment of a base for medical device electronic module;

FIG. 2 is a front view of the electronic module of FIG. 1;

FIG. 3 is a rear view of the electronic module of FIG. 1;

FIG. 4 is a right side view of the electronic module of FIG. 1;

FIG. 5 is a left side view of the electronic module of FIG. 1; and,

FIG. 6 is a top view of the electronic module of FIG. 1. The broken lines illustrate portions of the base for medical device electronic module that form no part of the claimed design.

1 Claim, 6 Drawing Sheets
